(57) **CLAIM**

The ornamental design for a book end, as shown and described.

DESCRIPTION

FIG. 1 is a perspective view of a book end showing my new design;

FIG. 2 is a front-elevational view thereof;

FIG. 3 is a rear-elevational view thereof;

FIG. 4 is a left side-elevational view thereof;

FIG. 5 is a right side-elevational view thereof;

FIG. 6 is a top plan view thereof; and,

FIG. 7 is a bottom plan view thereof.

The broken lines immediately adjacent to the shaded areas depict the bounds of the claimed design, while all other broken lines are directed to environment. The broken lines form no part of the claimed design.

1 Claim, 7 Drawing Sheets(56)
